[57] CLAIM

The ornamental design for a soldering iron with removable cap, as shown and described.

DESCRIPTION

FIG. 1 is a one end perspective view of the soldering iron with removable cap showing our new design;

FIG. 2 is an opposite end perspective view thereof;

FIG. 3 is a side elevational view thereof;

FIG. 4 is an end elevational view thereof;

FIG. 5 is an opposite end elevational view thereof;

FIG. 6 is a one side and one end perspective view of the soldering iron with removable cap showing the iron portion of our new design, the cap being omitted for clarity of disclosure only;

FIG. 7 is an opposite side perspective view thereof;

FIG. 8 is a perspective view thereof similar of FIG. 7 but with the switch in an alternate position;

FIG. 9 is an opposite end perspective view thereof;

FIG. 10 is a side elevation view thereof;

FIG. 11 is a one end perspective view of the cap portion thereof, the tool being omitted for clarity of disclosure only;

FIG. 12 is an opposite end perspective view of the cap portion thereof, the tool being omitted for clarity of disclosure only.
